UNITED STATES PATENT OFFICE.

HENRI GEORGE AND JEAN HEBERT, OF PARIS, FRANCE.

ELECTRICAL CONDUCTOR.

1,334,850.

Specification of Letters Patent. Patented Mar. 23, 1920.

Application filed January 31, 1919. Serial No. 274,334.

To all whom it may concern:

Be it known that we, HENRI GEORGE, engineer, a citizen of the French Republic, residing 167 Rue de Vaugirard, Paris, in the 5 Republic of France, and JEAN HEBERT, engineer, a citizen of the French Republic, residing 31 Avenue d'Eylau, Paris, France, have invented certain new and useful Improvements in and Relating to Electrical 10 Conductors, of which the following is a specification.

This invention has for its object to provide an improved insulated and unalterable electrical conductor capable of being used 15 for electrical purposes. The improved conductor consists essentially of a conducting wire of difficultly fusible substance inclosed in any insulating and non-porous material refractory to high temperatures.

20 The manner in which this invention is to be performed will now be more particularly described with reference to the accompanying drawings which illustrate by way of example some constructional forms of this 25 invention.

In these drawings:

Figure 1 is a section of a device according to this invention constituting a tight electrode.

30 Fig. 2 is a section of a heating element.

Fig. 3 is a view of a spiral-shaped heating element.

Fig. 4 is a section of a vertical heating element comprising a long length of wire, 35 and

Fig. 5 is a section of a horizontal element or tube for heating currents of gas and liquid.

In carrying this invention into effect, a 40 wire *b* of tungsten is inserted into a tube *a* of quartz (Fig. 1) of suitable dimensions. The tungsten wire is sealed for instance by means of the blow-pipe, in a mass of quartz *c*. The tungsten wire which is sealed in the 45 quartz is in sufficiently intimate contact therewith to constitute a tight joint. It may serve as an electric terminal for all electrical apparatus made of quartz designed to hold a vacuum or a pressure and to contain 50 any solid, liquid or gaseous bodies, such as for instance quartz glow lamps, rarefied gas apparatus, laboratory apparatus, mercury vapor lamps or rectifiers.

Fig. 2 is a section of a heating element 55 for all purposes; a number of elements of this type may be grouped in any desired

manner and connected in series or in parallel.

The tungsten wire *b* is embedded in a mass of quartz *d* ending in cups *e* which contain 60 a suitable conductive cementitious sealing material *f* and are covered by metal caps *g* for receiving the connections *h*. The metal caps form electrical contact with the conductive sealing material *f* which is in turn 65 in electrical contact with the tungsten wire.

The invention may also be performed by embedding a tungsten wire *b* (Figs. 4 and 5) in either a quartz rod *i* (Fig. 4) or in a quartz tube *k* (Fig. 5). This latter modification is particularly suitable for heating currents of gas and liquids. The tungsten wire may be embedded in either the rod or tube by winding the wire upon a suitable rod or tube of quartz, and then placing a 75 tube of quartz over the wire, thus wound, and then melting the whole to a homogeneous mass as by means of a suitable blow pipe.

The improved apparatuses thus produced 80 by embedding a tungsten wire in a mass of quartz, constitute joints that will resist high temperatures (1000°), as well as sudden changes of temperature.

When an apparatus of this kind is raised 85 to 1000°, it can be plunged suddenly into water without untoward results. The tungsten wire is protected from the action of the surrounding atmosphere, such as the oxygen of the air, moisture, acid vapors, chemical 90 products. It can be raised by the passage of an electrical current to a dazzling white heat without being vaporized or deteriorated thereby. Further, it has been found by experience that even under such conditions the 95 quartz resists perfectly and never breaks, so that it can be used with all heating devices and processes, as well as in some cases of electrical lighting, and likewise in rheostats of all kinds operating in any medium.

100 The wire when traversed by an intense current, becomes hot only slowly owing to the conducting away of the heat by the mass of quartz in which it is embedded and by convection of the air around the outer surface of the quartz. This allows of constructing starting rheostats for high intensities with a very small bulk, since the density of the current may in such apparatus exceed 350 amperes per square millimeter of 110 cross section.

Owing to the embedding of the wire, the

latter is electrically insulated in a perfect manner.

What we claim is:

1. An insulated and unalterable electrical conductor which consists of a conducting wire of difficultly fusible substance embedded in fused insulating and non porous material that is refractory to high temperatures.
- 10 2. An electrical conductor as claimed in claim 1, consisting of a tungsten wire embedded in a mass fused quartz.
- 15 3. An electrical conductor as claimed in claim 1, consisting of quartz insulation in which is embedded a tungsten wire serving as a terminal for any quartz apparatus.
4. An electrical conductor as claimed in claim 1, consisting of a tungsten wire em-

bedded in a mass of quartz terminating in cups which contain an electric conductive sealing material and are covered with metal caps for receiving the connections.

5. An electrical conductor as claimed in claim 1, consisting of a quartz insulation of suitable conformation in which is embedded tungsten wire and upon which is supported suitable terminals.

In testimony whereof we have hereunto set our hands at Paris (France), this 15th day of January, 1919.

HENRI GEORGE.
JEAN HEBERT.

In the presence of two witnesses:

JOHN F. SIMONS,
EMILE BERTRONOL.
